CLAIM

The ornamental design for a class ring, as shown and described.

DESCRIPTION

FIG. 1 is a top plan view of a class ring showing our new design;

FIG. 2 is a left side elevational view thereof;

FIG. 3 is a front elevational view thereof;

FIG. 4 is a left side elevational view of a class ring showing a second embodiment of our new design;

FIG. 5 is a top plan view of the embodiment in FIG. 4;

FIG. 6 is a fragmentary right side elevational view of a class ring showing a third embodiment of our new design;

FIG. 7 is a top plan view of the embodiment in FIG. 6;

FIG. 8 is a fragmentary left side elevational view of a class ring showing a fourth embodiment of our new design;

FIG. 9 is a top plan view of the embodiment in FIG. 8;

FIG. 10 is a fragmentary right side elevational view of a class ring showing a fifth embodiment of our new design; and

FIG. 11 is a top plan view of the embodiment in FIG. 10.
